(57) **CLAIM**

The ornamental design for an X-ray detector, as shown and described.

DESCRIPTION

FIG. 1 is a front perspective view of an X-ray detector, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the portion, '9' in FIG. 1;

FIG. 10 is an enlarged view of the portion, '10' in FIG. 8;

FIG. 11 is an enlarged view of the portion, '11' in FIG. 8;

FIG. 12 is a front perspective view of another embodiment of an X-ray detector, showing my new design;

FIG. 13 is a front view thereof;

FIG. 14 is a rear view thereof;

FIG. 15 is a left-side view thereof;

FIG. 16 is a right-side view thereof;

FIG. 17 is a top view thereof;

FIG. 18 is a bottom view thereof; and,

FIG. 19 is a rear perspective view thereof.

The dot-dash broken lines encircling enlargement portions of the design form no part of the claimed design. The broken lines illustrating portions of the X-ray detector form no part of the claimed design.
